UNITED STATES PATENT OFFICE.

CARL VORWERK, OF BARMEN, GERMANY.

JACQUARD MECHANISM.

No. 814,337.

Specification of Letters Patent.

Patented March 8, 1906.

Application filed October 5, 1903. Serial No. 175,748.

To all whom it may concern:

Be it known that I, CARL VORWERK, a subject of the German Emperor, residing at Barmen, in the Rhine Province, Prussia, Germany, have invented certain new and useful Improvements in Jacquard Mechanism, of which the following is a specification accompanied by drawings.

This invention relates to jacquard mechanism enabling the figuring warp-threads to be lifted or lowered at each card the varying distances required to bring the proper yarns in line in accordance with the pattern to be produced.

The objects of the invention are to improve upon the construction of the same mechanism and increase the efficiency of the apparatus.

Further objects of the invention will hereinafter appear; and to these ends the invention consists of apparatus for carrying out the above objects embodying the features of construction, combinations of elements, and arrangement of parts having the general mode of operation substantially as herein-after fully described and claimed in this specification and shown in the accompanying drawings, in which—

Figure 1 is a side elevation, partly in section, of the improved jacquard mechanism constructed in accordance with this invention. Fig. 2 is an edge view of the improved peg-strip. Fig. 3 is a side view of the peg-strip. Fig. 4 is an enlarged detail broken face view of the needle-plate.

In the jacquard apparatus hitherto employed the needles pushing the pegs against the strips or bars for lifting the pile-yarn carriers are arranged more or less obliquely relatively to a horizontal line, as the distance of the pegs from each other must necessarily be much greater than that of the needles from each other in the plate facing the pattern-cards. There are disadvantages in this oblique arrangement, for the needles do not move easily enough, which results in much trouble and loss of time. In order to obviate these disadvantages according to this invention, the needles are disposed horizontally, combining a springless set 12 with a spring set 13, and each springless needle 12 is con-

nected with a vertical needle 14. These vertical needles 14 can be very thin and numerous and arranged very closely together, thus allowing the use of relatively thin, small, manageable, and cheap paper cards and affording provision for the use of many "frames" or "colors" (independent colors,) if desired, up to as many as thirty-three in this instance, whereas the mechanism hitherto used does not afford provision for substantially more than eleven. The peg-strips 15 are equal in number to the yarn-carriers which are suitably suspended to them, as by means of wires, so that every lift given to a peg-strip is imparted to the corresponding yarn-carrier. The peg-strips 15 are guided by top and bottom comb-frames 16 and 17, stop-pieces 18 preventing them from dropping too low. Every strip 15 is provided with as many holes as the yarn-carriers, and also the distance of the holes from each other is exactly the same as that of the holes in the yarn-carriers. In the holes of the strips are fitted movable pegs 19. Opposite every peg 19 is a horizontal needle 13, guided by the plates 20, 21, and 22. These needles have small bosses 23 and spiral springs 24.

Opposite the needles 13 and corresponding to them in number are the needles 12 with heads 25. Every such needle passes through the guide-plate 26 and through the eye of the corresponding vertical needle 14. These vertical needles are guided by the top frame 27 and bottom frame 28. Below these needles 14 is a card-cylinder carrying and moving the design-cards. Facing the free ends of the horizontal needles is a pushing-grate 30 with the pusher-rules 31, which grate has a forward and backward movement actuated by any suitable means. At the opposite side, facing the ends of the pegs 19, is a pushing-plate 32, which also has a forward and backward movement imparted thereto by any suitable means, and adjacent to the strips 15 is a lifting-bar 33, which has an up and down motion imparted thereto.

The needles 12 and 14, the plates 22, and the pushers 31 form the pitch-reducing device, as shown in United States Patent No. 346,877, granted August 3, 1886, to Jules Verdol, for a jacquard-machine, and the ac-

tuating apparatus illustrated in that patent is one suitable form of operative actuating mechanism for the parts mentioned, although any other suitable operative means may be 5 provided.

The operation of the apparatus is as follows: The card-cylinder 29, guide-bar 28, and the readjusting-plate above the top guide-plate 27 are raised together, whereby in each 10 row of needles corresponding to one peg-strip all but one of the needles are pressed upward by blanks or imperforated portions of the cards, the remaining needle of each row being that which corresponds with the 15 color indicated by the design and for which, therefore, a hole had to be stamped into the card, so that the needle can enter the corresponding hole of the cylinder-plate, and thus remain stationary. Each vertical needle 14 20 being pressed upward raises the free end of its corresponding horizontal needle 12 to such a height that this end clears the vertical side of the pusher-rule 30, whereas the horizontal needles 12 of those vertical needles 14 25 not pressed back, but which have entered the holes, remain in their position. The pushing-grate 30 is then moved forward and pushes the latter needles against their corresponding spring-needles, and these push back 30 the pegs 19 against the strips 15, from which all the pegs are projecting at first toward the plate 20, so that these pegs, one for every strip, now project beyond the opposite side of the strips. The card-cylinder 29, guide-bar 35 28, the readjusting-plate above the top guide-plate 27, and the pushing-grate 30 are now returned, so that those vertical needles which were pushed upward drop back or are forcibly replaced in their former position. Those 40 horizontal needles 12 which were pushed forward are returned by the readjusting-plate 22, while the corresponding horizontal needles 13 are pressed back to their first position under the action of the spiral springs 24 or 45 are forcibly returned by a readjusting-plate. Then the lifting-bar 33 is raised to the position 33^a, and in its movement it catches the one projecting peg of every strip, thus lifting the strips to an extent equal to one or more holes, 50 according to the particular peg that projects as previously selected by the card, and the corresponding yarn-carriers are lifted thereby to the same extent to bring their pile-threads into the horizontal line at which the gripper-points act. Then the loom goes through various movements, the lifting-bar 33 and the strips 15 are allowed to come down to their former position, and the pushing-plate 32 moves against the strips and pushes the selected pegs back, so that all the pegs are 55 projecting again at the side toward the needles, 60

as represented in Fig. 1, ready for the next action after the return of the pushing-plate 32.

The peg-strips hitherto used have been provided with simple pegs with heads at one 65 side and were freely movable. This, however, entails the drawback that the pegs are liable to be shaken back and forth by vibration when the loom is running, whereby the pegs are damaged by the lifting-bar 33, Fig. 70 1, which consequently damages the strips and needles, and, furthermore, the yarn-carriers, the fabric, and the cards. In order to remedy these defects, I employ means for effecting a brake or frictional action upon the pegs—as, 75 for example, by means of springs 36, Fig. 3, which are fixed in the recesses of the strips. Collars 35 in this instance prevent the pegs from moving too far. Another improvement 80 consists in the means for removing the single spring-needles 13 out of the needle-plate 21, Fig. 1. Great trouble has hitherto been found in removing such a needle when injured by bending. It has always been necessary to remove all of the needles up to the one 85 which has been bent before the bent needle could be gripped. To obviate such an inconvenience, I provide in the plate 21 additional holes between the small holes for the needles, said additional holes being large 90 enough to permit the collars on the needles to pass through, and the arrangement is such that through each of these additional holes two needles of the row above and two needles of the row below can be removed, it only 95 being necessary to first remove the pushing-grade 30, the needles 12 and 14, and the guide-plates 22 and 26, and this can readily be done all at the same time, as these parts are connected in such manner as to form one piece. 100

Obviously some features of this invention may be used without others, and the invention may be embodied in widely-varying forms.

Therefore, without limiting myself to the 105 construction shown and described nor enumerating equivalents, I claim, and desire to obtain by Letters Patent, the following:

1. In a jacquard mechanism, the combination with peg-strips provided with movable 110 pegs, of corresponding straight parallel spring-needles, corresponding straight parallel springless needles, and vertical needles each operating in conjunction with one of the horizontal springless needles and corresponding 115 to one hole in the card-cylinder, for substantially the purposes set forth.

2. In a jacquard mechanism, the combination with peg-strips and movable pegs a set 120 of horizontal needles and a set of vertical needles connected to operate in conjunction therewith and being controlled by the pat-

tern-cards, of a second set of horizontal needles opposite the pegs of the peg-strips, for substantially the purposes set forth.

3. In a jacquard mechanism, the combination of peg-strips provided with movable pegs, and means for preventing these pegs from shaking back and forth under vibration, for substantially the purposes set forth.

4. In a jacquard mechanism, the combination with the spring-needles, of a guide-plate

provided with apertures for removing the spring-needles out of the needles-case, for substantially the purposes set forth.

In testimony whereof I have signed this specification in the presence of two subscribing witnesses.

CARL VORWERK.
